UNITED STATES PATENT OFFICE

115,771

DESIGN FOR A MOTION PICTURE PROJECTOR

Philmore F. Sperry, Chicago, Ill., assignor to
Revere Camera Company, Chicago, Ill., a cor-
poration of Delaware

Application June 3, 1939, Serial No. 85,323

Term of patent 14 years

To all whom it may concern:

Be it known that I, Philmore F. Sperry, a citizen
of the United States, residing at Chicago, in
the county of Cook and State of Illinois, have
invented a new, original, and ornamental Design
for Motion Picture Projectors, of which the fol-
lowing is a specification, reference being had to
the accompanying drawings, forming part
thereof.

Fig. 1 is a plan view of a motion picture pro-
jector showing my new design;

Fig. 2 is an elevation of one side of the pro-
jector;

Fig. 3 is an elevation of the other side of the
projector;

Fig. 4 is a front view of the projector; and
Fig. 5 is a back view of the projector.

I claim:

The ornamental design for a motion picture
projector, as shown.

PHILMORE F. SPERRY.
